PROCESS FOR MAKING FENDERS

David James Dunlop, Pontiac, Mich., assignor to
 General Motors Corporation, Detroit, Mich., a
 corporation of Delaware

Application August 31, 1949, Serial No. 113,373

7 Claims. (Cl. 113—116)

1

This invention relates generally to deep drawn sheet metal articles, and particularly to an improved method for making such articles in one piece from flat stock.

While the invention is applicable to the forming of various articles from sheet metal and the like where a relatively deep draw is required, it is particularly advantageous in the forming of automotive front fenders which incorporate an opening in the front wall for the headlight, and I have chosen such an embodiment for purposes of illustration.

One aspect of the trend in modern automotive vehicle design has been to raise the crown of the front fenders to a height more and more nearly equal to that of the vehicle hood. This has resulted in greater extensions of the skirt and front wall sections of the fender to maintain the same shielding coverage of the wheels, which in turn necessitates a deeper draw of the metal to form the fender in one piece from a flat blank. As is well known in this art, the deeper the draw required the greater tendency there is for the metal to wrinkle and tear during the forming operation, with resultant increased labor and expense required in the finishing operation. Further, the greater forces applied to the metal in making deep drawn articles requires that larger blank holding portions must be provided, which are trimmed off as waste material after the drawing operation.

It is the object of my invention to provide an improved method for making so-called "deep-drawn" vehicle fenders and the like which substantially reduces the depth of draw required to obtain the shape and form desired.

My improved method contemplates the formation of a generally flat blank of suitable size and contour having a notch or gore extending inward from one edge in the section of deepest penetration by the draw punch, bending the blank into a dished, such as substantially cone or partial cone shape and welding or otherwise securing together the marginal edges of the notch, and then placing the dished blank between dies and drawing it to final shape. The notching of the blank and pre-forming it to a dished shape before the drawing operation makes the blank conform much closer to the shape of the draw die than it would if flat, and consequently the amount which the metal needs to stretch in assuming its final shape is considerably less. In applying my invention to the forming of front fenders for automotive vehicles which are to have an opening in the front wall for a headlight, the notch

2

is preferably located in the section of this opening so that the subsequent removal of material for that purpose will eliminate a substantial portion of the notch seam in the finally completed fender.

In the drawings:

Figure 1 is a perspective view of a flat sheet from which the portion shown in broken lines is stamped out to provide a blank for making an automotive vehicle front fender, a notch being provided in one end of the blank in accordance with my invention.

Figure 2 is a perspective view schematically showing suitable apparatus for effecting the bending of the flat blank of Figure 1 first into the V shape shown in Figure 3 and thence into the conical shape of Figure 5.

Figure 3 is a perspective view of the blank after being bent to V shape along a longitudinal axis which passes through the vertex of the notch.

Figure 4 is a plan view of a portion of the apparatus of Figure 2, showing the operational step of bringing together the edge portions of the notch to obtain the partially conical shape of the blank shown in Figure 5.

Figure 5 is a perspective view of the blank after the edge portions of the notch have been brought together and welded in overlapping relation, causing the blank to assume a generally conical shape.

Figures 6 and 7 are transverse and longitudinal section views of the final stamping operation as performed in the draw die.

Figure 8 is a perspective view of the formed fender after removal from the draw die.

With more particular reference to the drawings, it will be seen that my improved method as applied to the making of an automotive vehicle front fender begins with the cutting out of a flat blank 1 shown in broken outline in Figure 1 from a flat sheet 2. The size and shape of this blank will of course, depend on the design of the particular fender to be made, it being considered necessary in this respect only to point out the front section 3 is made somewhat wider than is conventional and has a generally V-shaped notch 4 in its forward edge 5. The provision of this notch is essential to my invention, and while it may be located otherwise than as shown, its location as illustrated is preferred for reasons which will be pointed out hereinafter. As shown, the notch 4 is disposed symmetrically of a generally longitudinal axis X of the blank 1, which axis will constitute the so-called "crown line" of the finally completed fender. The edges 6 and

7 which define the notch are substantially the same length and both intersect the axis X at point 8 which constitutes the vertex of the notch and the apex of the cone or partial cone into which the blank is subsequently shaped. Preferably one edge e. g. 6 is cut straight throughout its length while the other edge 7 angles off rearwardly just short of the vertex point 8 as shown at 9 to provide for a generally uniform width of overlap by the notch edges 6 and 7 when the portions of the blank adjacent these edges are, subsequently bent into a partial cone shape.

The blank 1 is then pre-formed to the generally conical shape shown in Figure 5, wherein the notch 4 which formerly existed is now closed up by the edges 6 and 7 thereof having been brought together into overlapping relation and permanently thus secured as by welding at 10. While this operation may be accomplished in various ways and in either one step or several steps, I have found it preferable to carry it out in a manner which will now be described. I first bend the blank into a V-shape as shown in Figure 3, the bend line 11 being coincident with the axis X previously referred to, then force the front portions 3' and 3'' on opposite sides of the bend line 11 toward each other until the notch edges 6 and 7 overlap, and finally weld these overlapping edges together as shown at 10 in Figure 5. These operations could be carried out by hand, of course, or the bending of the blank to the V-shape of Figure 3 could be performed on a standard sheet metal break and the remaining operations completed by hand.

In Figures 2 and 4 is schematically shown an apparatus which has proven very convenient for effecting this conical pre-forming of the blank in mass production. This consists essentially of a die frame or block 15 which is longitudinally movable on guides indicated by the ways 16 and 17 toward and away from a stationary die block 18 by any power means such as an air cylinder not shown. The upper face 19 of the movable block 15 is trough or V-shaped to provide a depression into which the flat fender blank may be forced to effect the bending of the latter along the axis X (line 11 in Figures 3-5). Downward pressure on the flat blank is effected by an arm 20 which is also movable by suitable power means not shown, this arm 20 being schematically shown as a plate hinged at 21 to the block 15 along one side edge of the latter's V-shaped upper face 19. When the arm or plate 20 is swung from its position as shown in solid lines to its broken line position in Figure 2, its free edge 22 forces the blank to bend along the axis X. Any suitable holding means, such as the dowel pins indicated in broken lines at 23 and 24 which project upwardly from the block 15 to engage holes provided therefor in one side of the blank, may be employed to anchor one side of the blank to insure uniform location of the bend line 11. Figure 3 shows the shape of the blank after the operation just described.

While the blank is still in the block 15 and after the arm 20 has been returned to its upraised position shown in Figure 2 the block 15 is moved toward the stationary die block 18 to effect the closing of the notch 4 by bringing the notch edges 6 and 7 into overlapping relation. During this movement of the block 15, the end wall 25 abuts the rear edge of the blank to insure its concurrent movement toward the stationary die block 18. This latter block is provided with a conically shaped face 26 which serves to cam

the blank end portions 3' and 3'' into notch closing relation as the blank is forced toward the same by the die block 15. The portion of the die face 26 which receives the blank end portion

5 3' is offset slightly from the portion which receives the blank end portion 3'' in order to insure that the notch edges 6 and 7 of the blank will overlap properly when they come together as will be clear from the plan view shown in Figure 4.

10 While the blank is still in the block 15 and the end portions are held in notch closing position as shown in Figure 4, the edges 6 and 7 are welded together. The interior of the bent-up blank is

15 accessible for one of the welding electrodes, and a slot 27 which is provided in the stationary block 18 allows access for the other electrode. These electrodes, which are not shown, may be of any desired type. Figure 5 shows the blank as completely pre-formed preparatory to the draw die operation. It will be understood that in the operations thus far described no drawing or stretching of the blank has been required, other than that locally associated with its being bent along the line 11.

20 25 The dished shape obtained during the pre-forming operations enables the blank to more closely conform with the shape of the draw die and punch than does a flat blank, thereby reducing the amount of draw necessary to effect 30 the desired final shape of the blank shown in Figure 8.

Referring to Figures 6 and 7, numeral 30 represents a draw die and 31 is the punch which co-35 operates therewith in the usual manner. Associated with and surrounding the punch 31 is the blank holding member 32, which cooperates in

40 abutting relation with the outer marginal upper face 33 of the draw die prior to the advancement of the punch and holds the blank's marginal edge portions during the draw. Also shown is the ejector 34 which is reciprocably mounted in the draw die opposite the punch and actuatable as by the air cylinder 35 to force the completed

45 36, 37 and 38 are projecting hardened 50 inserts carried by the blank holder which depress the blank marginal edge portions into cooperating grooves provided therefor in the upper face of the die block, further insuring against slippage of the blank relative to the blank holder during the draw.

The blank 1 is shown in solid section lines between the working surfaces 39 and 40 of the punch and die, respectively, the shape which it 55 assumes following the draw being clearly evident. The broken outline 41 in Figures 6 and 7 represent the longitudinal and transverse sectional configurations of the blank in its preformed condition of Figure 5, prior to the start of the draw die operation.

60 65 The spacing between this broken outline 41 and the fully drawn blank 1 clearly demonstrates the considerable reduction in depth of draw required by my method over that which would result from drawing the fender from the conventional flat blank.

T, T', T'' and T''' in Figures 6 and 7 indicate the location of the trim lines at which the blank 1 is trimmed of excess metal following its removal from the draw die. It will be noted that 70 these trim lines, particularly those designated T, T' and T'', are relatively close to the marginal extremities or edges 5, 42 and 43 of the blank, and that there is thus only a relatively narrow section of material which is trimmed off as scrap material. One of the factors responsible for this

small amount of trim scrap is that the conically pre-formed blank of Figure 5 possesses the necessary shape at its marginal edge portions to substantially conform to the marginal upper face 33 of the draw die prior to the drawing operation, which enables the use of a portion of the usable fender section of the blank adjacent the trim lines for blank holding purposes. One example of this condition is clearly apparent in Figure 6 wherein the portion 45 of the blank inwardly of the trim line T' is shown disposed opposite the blank holder 32. Another factor, is of course the reduced amount of draw required by reason of the substantial extent of uniformity of the dished shape blank to the draw die and punch, which in turn requires less force to effect the draw and consequently a smaller gripping area on the blank for the blank holder.

The notch 4 is preferably located in the forward edge 5 of the blank as earlier described where the completed fender is to house a headlamp having its lens opening 50 in the front wall 51, since the latter opening will eliminate the upper and substantially greater portion 52 of the welded seam 53. The headlamp lens opening 50 is preferably formed subsequently to the draw die operation, employing any suitable blanking means for the purpose. Other locations for the notch 4 could be made, such as on either side and near the front of the fender within the scope of my invention. The most important factor in the location of the notch is that it be in a section of the fender where the greater portion of the draw is normally to occur.

Further, while I have described my invention with specific reference to the forming of automotive fenders, the principles thereof are applicable to the forming of any so-called "deep-drawn" article.

I claim:

1. A method of forming a drawn hollow sheet metal unit which would normally require a deep draw or a plurality of drawing operations from a single flat metal blank, comprising the steps of notching the blank inwardly from one edge, said notch extending into the area to be drawn, bending the blank to bring the edges of the notch together to form a dish-shaped article having its apex coincident with the vertex of the notch, securing the edges of the notch together by integral joining means of sufficient strength to prevent rupture during the subsequent drawing, and then drawing said article into the desired shape of the hollow metal unit.

2. The method of claim 1, including after notching, bending the blank into a V-shape about an axis extending through the vertex of the notch.
3. The method of claim 1 as applied to the forming of a vehicle fender having generally vertical walls depending from a top wall, wherein the notch is formed in the section of the blank which is to constitute a vertical wall of the fender.
4. The method of claim 1 as applied to the forming of a vehicle fender having end and side wall portions depending from a top wall portion, wherein the notch is formed in the section of the blank which is to constitute an end wall portion of the fender.
- 10 5. The method of claim 1 as applied to the forming of a vehicle fender having end and side wall portions depending from a top wall portion, wherein the notch is formed in the section of the blank which is to constitute an end wall portion of the fender, and including the step, after drawing, of cutting an opening in said end wall portion displacing a portion of said joined edges.
- 15 6. The method of claim 1 as applied to the forming of a vehicle fender having end and side wall portions, wherein the notch is formed in the section of the blank which is to constitute an end wall portion of the fender, and including the step, after notching, of bending the blank to a V-shape about a longitudinal axis extending through the vertex of the notch.
- 20 7. The method of claim 1 as applied to the forming of a vehicle fender, including after notching, bending the blank longitudinally through the notch by moving the marginal edge portions of the blank on opposite sides of the blank into substantially the angular relation which said portions bear to each other after the draw step.
- 25 30 35
